mesne assignments, to North American Philips Company, Inc., New York, N. Y., a corporation of Delaware

Application November 2, 1955, Serial No. 544,514

Claims priority, application Netherlands
November 3, 1954

5 Claims. (Cl. 250—103)

The present invention relates to an X-ray tube voltage control circuit.

X-ray tubes are usually accompanied by one or more regulating devices, for example, a device for selecting the voltage between the anode and the cathode of the X-ray tube (tube voltage) and also a regulating device for adjusting the current which serves to heat the incandescent cathode of the X-ray tube. The regulating device permits the control of the electron emission in the X-ray tube (tube current).

In certain cases, steps are taken to make the tube current independent of the position occupied by the voltage selector. These steps afford the advantage that the different load values may be adjusted more easily in taking X-ray photographs. When the required tube voltage as a function of the object to be photographed has been determined, it is possible to ascertain how much the product of tube current and exposure time, hence the charge, must be to obtain a determined blackening of the photographic plate. The charge adjusted by the current regulator and the time selector may be indicated on a reading scale which is usually calibrated in units representing the product of milliamperes and seconds. If the tube current is dependent upon the tube voltage, a different millampere-scale is required for any tube voltage to be selected. If, however, the tube current does not vary as a result of variation in voltage, the same millampere-scale may serve for any voltage selected.

Several means may be utilized to make the tube current independent of the position of the voltage selector. It is possible, for example, to include a variable resistor in the heating-current circuit of the X-ray tube and to couple its regulating member to the regulating member which serves to select the tube voltage. As an alternative, for the same purpose, use is made of a transformer, the primary voltage of which is controlled by means of an operating member coupled to the voltage selector and the secondary winding of which is included in the heating-current circuit. The effect of such steps is not very accurate as a result of the fact that the tube voltage is determined not only by the position of the voltage selector, but also by the voltage drop across the different resistances, which voltage drop varies with the current strength. Consequently, they can lead to perfect correction only for a predetermined value of the tube current.

For varying the tube voltage, use is made of a transformer of adjustable transformation ratio. The voltage drop resulting from the resistance in the primary thereof varies not only with the tube current, but also with the transformation ratio.

The X-ray tube is usually accompanied by a graph showing a plurality of curves each corresponding to a predetermined current and indicating the tube voltage as a function of the transformation ratio of the regulating transformer. The graph indicates the position which the voltage selector must occupy to produce a determined tube voltage for a given tube current. As an alternative, use may be made of a table showing the re-

2

quired position of the voltage selector for each combination of tube current and tube voltage. The positions are usually each indicated by a number on the reading scale associated with the operating member.

5 The production of such a graph requires a plurality of measurements with the X-ray tube for each position of the voltage selector, in each case for a series of values of the tube current. At the place of installation of the tube, the resistance is definitely adjusted to the value 10 on which the graph is based.

An object of the invention is to facilitate the production of the voltage graph and the adjustment of the tube voltage. For this purpose, the X-ray tube control circuit of the present invention comprises means for insuring that the voltage drop for any position of the voltage selector is constant for a given value of the tube current. In this case the lines of the voltage graph are straight and the tube voltage for a series of values of the tube current is to be determined in only one position of 20 the voltage selector.

The person in charge of the adjustment of the different load values for an X-ray circuit in accordance with the invention will sooner be able to operate the voltage selector without consulting the graph, since the nominal

25 value associated with an arbitrary position of the voltage selector need only be decreased (or increased) by an amount equal for all positions to obtain the value of the actual tube voltage, which amount is otherwise also dependent upon the tube current.

30 According to the invention, the selector for the tube voltage is coupled to a variable resistor included in the supply circuit of the X-ray tube, so that the impedance in this circuit, and hence the voltage drop, varies when the voltage varies. When in a manner which will be explained hereinafter, the resistance value required of said resistor is calculated for the various positions of the voltage selector to maintain constancy of the voltage drop, a non-linear relation between the impedance and the transformation ratio of the regulating transformer is 35 found. However, it appears that no error of consequence arises when use is made of a resistor, the regulating steps of which are proportional to those of the transformation ratio, provided that care is taken to insure that the voltage drop is substantially equal at least 40 at the boundaries of the regulating range of the tube voltage.

The control circuit of the present invention may alternatively be designed so that the tube voltage is no longer dependent upon the position of the current regulator. In this case it is no longer necessary to consult 50 a graph, or a table, or to keep in mind a series of correction values, in order to adjust the tube voltage; the reading scale associated with the member for operating the voltage selector may be provided with a number indicating directly the value of the tube voltage for each 55 position of said member.

For this purpose, an auxiliary voltage is added to the supply voltage for the X-ray tube. The auxiliary voltage is constant for any transformation ratio of the regulating 60 transformer, but varies with the tube current. Consequently, it may be chosen by the operating member of the current regulator.

Thus, the tube current varies to an even lesser extent 65 than previously, when a different tube voltage is chosen. The small variation which still occurs due to the auxiliary voltage, instead of being determined by the tube current itself, is determined by the position of the regulating member of the tube current and is no longer of importance.

70 Finally, the tube current regulator may be coupled in known manner to a timing device for selecting the duration of load, so that the tube current decreases with an

increase in the duration of load, and conversely. It is thus possible always to obtain automatically the optimum load on the tube and to avoid overload of the tube.

In order that the invention may be readily carried into effect, it will now be described, by way of example, with reference to the accompanying drawing, in which:

Fig. 1 is a schematic diagram of an equivalent circuit of an X-ray tube voltage control circuit; and

Fig. 2 is a schematic diagram of an embodiment of the X-ray tube voltage control circuit of the present invention.

The cause of the voltage drop and the manner in which its value may be determined, may be observed by reference to Fig. 1. In Fig. 1, the regulating transformer, which is of the autotransformer type, and the high-tension transformer, are indicated by T_1 and T_2 , respectively. The variable transformation ratio of the autotransformer is represented by N_1 and the constant transformation ratio of the high-tension transformer is represented by N_2 . When the voltage of the power supply, which may be regarded as constant, is represented by E_n , then the tube voltage which occurs when the tube current has the value zero (no-load voltage) is $E_0 = N_1 N_2 E_n$.

The resistance of the primary circuit in the regulating transformer is represented by a concentrated resistor R_n in Fig. 1, the remaining resistance in the primary circuit of the high-tension transformer being represented therein by a concentrated resistor R_a . The resistance of the secondary circuit of the high-tension transformer, which is connected in series with the X-ray tube and includes the resistance of any rectifying tubes present, is indicated by a concentrated resistor R_t in Fig. 1.

The X-ray tube voltage, which is obtained when the X-ray tube current is switched on, is

$$E_b = E_0 - E_v$$

wherein E_v is the drop in voltage due to the resistances R_n , R_a and R_t . In other words, E_v is the difference between the no-load tube voltage and the loaded tube voltage.

When the tube current has a value I the voltage drop may be represented by

$$E_v = I(R_t + R_a N_2^2 + R_n N_1^2 N_2^2)$$

This comprises two components $I(R_t + R_a N_2^2)$ and $I R_n N_1^2 N_2^2$. The first component $I(R_t + R_a N_2^2)$ is not dependent upon the transformation ratio N_1 and the second component $I R_n N_1^2 N_2^2$ varies quadratically with N_1 .

It is to be noted that R_a actually is slightly dependent upon N_1 . However, by suitable adjustment of the resistance steps, erroneous resultant values are avoided.

The variation of the component $I R_n N_1^2 N_2^2$ of the voltage drop is neutralized by an additional variable resistor in the primary supply circuit of the high-tension transformer, the regulating member of which is coupled to that of the regulating transformer. Consequently, the value R_a varies when N_1 varies. In the equation

$$E_v = I(R_t + R_a N_2^2 + R_n N_1^2 N_2^2)$$

the value of E_v becomes independent of the adjustment of the voltage selector if

$$I R_a N_2^2 + I R_n N_1^2 N_2^2 = C$$

C represents a constant value. Thus, if

$$R_a = \frac{C}{I N_2^2} - R_n N_1^2$$

then for a current I the total voltage drop is the same for any value of N_1 . According to a further elaboration of the invention, in order to design the circuit so that for any position of the voltage selector the actual tube voltage may be indicated, said voltage being obtained for this position irrespective of the value of the tube current, the voltage included in the regulating transformer has added to it an auxiliary voltage E_h of a value such that $E_h - E_v$ is an amount which does not vary with I . Con-

sequently the term $E_h - (I R_t + I R_a N_2^2 + I R_n N_1^2 N_2^2)$ must be constant. When the expression

$$\frac{C}{I N_2^2} - R_n N_1^2$$

is substituted for R_a , the desired operating condition requires that $E_h - I R_t$ must provide a constant value and hence that the auxiliary voltage must vary in proportion with current.

Fig. 2 is a schematic diagram of an embodiment of the X-ray tube voltage control circuit of the present invention. A transformer 1, which is of the autotransformer type, is connected to the power supply terminals via a variable resistor 3. The resistor 3 serves to bring the impedance of the primary circuit of the regulating transformer 1 to that value which is used in calibrating the device or in providing the voltage graph. Said primary circuit also includes a regulator 4 which can connect one of the power supply lines 2 to different tapping points on the winding of the transformer 1. By means of the regulator 4, it is possible for a voltmeter 5, provided between two fixed points of the transformer winding, to be always adjusted to a prescribed indication irrespective of local variations in the power supply voltage.

25 The heating current for the cathode of the X-ray tube 6 is supplied by a heating-current transformer 7. Since several methods are known for maintaining the tube current constant, upon variation of the tube voltage, it is not necessary to refer thereto in detail. For the sake of completeness, a variable resistor 8 which serves to maintain the tube current constant, is shown in the primary circuit of the heating-current transformer 7. The regulating member of the resistor 8 is coupled to a voltage selector 13.

30 The heating current circuit also includes a voltage stabilizer 9 and a variable resistor tube current regulator 10. The resistor 10 serves to control the tube current.

The AC output in the secondary winding of a high tension transformer 12 is rectified by a rectifier bridge 14 and is supplied to the X-ray tube 6.

35 The regulating transformer 1 supplies the supply voltage to the high-tension transformer 12. The primary winding of the high tension transformer 12 may be connected, by way of the voltage selector 13, to different tapping points 15 on the winding of the regulating transformer 1.

The primary circuit of high tension transformer 12 includes a variable resistor 18, the regulating member of which is coupled to the voltage selector 13. The selector 13, the resistor 18 and the resistor 8 are coupled together mechanically, or in another manner, said elements being 40 shown connected together by a dot-and-dash line.

It is intended that, when the position of the voltage selector 13 is varied, the value of the resistor 18 be varied 45 in such a manner that the voltage drop is not affected by this variation in position. Although it has been determined that for this purpose the resistance value of the resistor 18 must vary quadratically with the transformation ratio of transformer 1, it has been found that for the comparatively small regulating range commonly used in practice, a linear variation provides sufficiently accurate approximation. The maximum value of N_1 to which the voltage selector 13 may be adjusted, is usually not higher than thrice the minimum value. For this regulating range, the maximum deviation which occurs when

50 the parabolic curve showing the resistor R_a as a function of N_1 is substituted by a straight line connecting the extreme points of this curve (hence the points associated with the maximum and minimum values of N_1 rendered possible by the voltage regulator) is not more than 20%.

55 The voltage drop is usually maintained below a reasonable limit by suitable choice of the various resistance values of the circuit and will seldom be more than 25% of the no-load voltage. In the most unfavorable case of substituting a resistor varying linearly with N_1 for a resistor varying with N_1 in the theoretically correct manner,

causes only an error of at most 5% and may therefore be regarded as coming within the scope of the invention.

The core of the regulating transformer 1 carries a separate auxiliary winding 16. The voltage induced in the winding 16 serves to make the voltage drop independent of the position of the regulator for the tube current. Due to the inclusion of the winding 16 in one of the supply lines to the high-tension transformer 12, the voltage induced in said winding constitutes a contribution to the supply voltage of said transformer.

As determined, the auxiliary voltage E_h produced in the winding 16 must vary with current. In order to achieve this, provision is made of a regulating member 17 which may be connected to different tapping points on the auxiliary winding 16 and which is coup'ed to the regulating member of the resistor 10 as shown by a dot-and-dash line. The regulating steps of the auxiliary winding 16 may best be determined empirically.

The supply current of the high-tension transformer 12 (at the beginning and at the end of the duration of load) is switched on and off by means of an electromagnetically operated switch 19. The energizing current of the switch 19 is controlled by a timer 11. If desired, the timer 11 may be coupled in known manner to the regulating member of the resistor 10 (as shown by a dot-and-dash line) so that either the X-ray tube is prevented from being loaded more strongly than is permissible for the chosen duration of load, or an optimum load on the X-ray tube is always obtained.

The variable resistor 18 may alternatively be included in the primary circuit, instead of in the secondary circuit, of the autotransformer 1. The condition that the regulating characteristic of the resistor theoretically has to satisfy in such a case may be readily determined from the foregoing equations. In this case, the auxiliary voltage of the auxiliary winding 16 must vary in proportion with the tube current.

It is to be understood that the invention is not limited to the details disclosed but includes all such variations and modifications as fall within the spirit of the invention and the scope of the appended claims.

Having thus set forth the nature of my invention, what I claim is:

1. An X-ray tube voltage control circuit, comprising an X-ray tube having an anode and a cathode, a source of power supply, transformer means having a variable transformation ratio and being coupled between said supply source and said anode and cathode of said tube, a selective member for varying the transformation ratio of said transformer means, variable impedance means having an impedance regulating member, said impedance means being interposed in the supply circuit of the anode between said supply source and said tube, and means for coupling said regulating member to said selective member, said impedance means at a first given position of said selector and regulating member having a value rendering the total voltage drop resulting from the load on the X-ray tube equal to that occurring at a second given position of said selector and regulating member.

2. An X-ray tube voltage control circuit, comprising an X-ray tube having an anode and a cathode, a source of power supply, transformer means having a variable transformation ratio and being coupled between said supply source and said anode and cathode of said tube, a selective member for varying the transformation ratio of said transformer means, variable impedance means having an impedance regulating member, said impedance means being interposed in the supply circuit of the anode between said transformer means and said tube and being variable in steps proportional to those of said transformation ratio, and means for coupling said regulating member to said selective member, said impedance means at a first given position of said selector and regulating member having a value rendering the total voltage drop resulting from the load on the X-ray tube equal to that occurring at a

second given position of said selector and regulating member.

3. An X-ray tube voltage control circuit, comprising an X-ray tube having an anode and a cathode, a source of power supply, transformer means having a variable transformation ratio and being coupled between said supply source and said anode and cathode of said tube, a selective member for varying the transformation ratio of said transformer means, variable impedance means having an impedance regulating member, said impedance means being interposed in the supply circuit of the anode between said transformer means and said tube and being variable in steps having intermediate values which are a quadratic function of said transformation ratio thereby to provide a substantially constant voltage drop through its entire regulating range, and means for coupling said regulating member to said selective member, said impedance means at a first given position of said selector and regulating member having a value rendering the total voltage drop resulting from the load on the X-ray tube equal to that occurring at a second given position of said selector and regulating member.

4. An X-ray tube voltage control circuit, comprising an X-ray tube having an anode and a cathode, a source of power supply, transformer means having a variable transformation ratio and being coupled between said supply source and said anode and cathode of said tube, a first selective member for varying the transformation ratio of said transformer means, variable impedance means having an impedance regulating member, said impedance means being interposed in the supply circuit of the anode between said transformer means and said tube, means for deriving a variable auxiliary voltage from said supply source, said last-mentioned means including a second selective member for varying said auxiliary voltage, means for coupling said regulating member to said first selective member, means for supplying a current to the cathode of said tube including further variable impedance means interposed between said supply source and the said cathode and having an impedance regulating member, and means for coupling the regulating member of said further variable impedance means to said second selective member whereby said auxiliary voltage varies with the current in the X-ray tube and differs by a substantially constant amount from the total voltage drop resulting from the load on said tube regardless of the position of the regulating member of said further variable impedance means.

5. An X-ray tube voltage control circuit, comprising an X-ray tube having an anode and a cathode, a source of power supply, transformer means having a variable transformation ratio and being coupled between said supply source and said anode and cathode of said tube, a first selective member for varying the transformation ratio of said transformer means, variable impedance means having an impedance regulating member, said impedance means being interposed in the supply circuit of the anode between said transformer means and said tube, means for deriving a variable auxiliary voltage from said supply source, said last-mentioned means including a second selective member for varying said auxiliary voltage, means for coupling said regulating member to said first selective member, means for supplying a current to the cathode of said tube including further variable impedance means interposed between said supply source and the said cathode and having an impedance regulating member, means for coupling the regulating member of said further variable impedance means to said second selective member, timing means, and means for coupling said timing means to the regulating member of said further variable impedance means whereby the current in the X-ray tube decreases with increasing duration of load on said tube and increases with decreasing duration of load on the said tube.
